CLAIM

The ornamental design for a telephone stand, as shown and described.

DESCRIPTION

FIG. 1 is a top, front and right-side perspective view of a telephone stand showing our new design;

FIG. 2 is a top plan view thereof;

FIG. 3 is a front-end-elevational view thereof;

FIG. 4 is a back-end elevational view thereof; and,

FIG. 5 is a left-side elevational view of the telephone stand, the right side being a mirror image thereof. The broken line showing of a handset and cord in FIG. 1 is for illustrative purposes only and forms no part of the claimed design.
